UNITED STATES PATENT OFFICE

GEBHARD C. BOHN, OF ST. PAUL, MINNESOTA

REFRIGERATOR

Application filed September 19, 1927. Serial No. 220,395.

The present invention relates to an improvement in refrigerator construction.

In the construction of refrigerators the joints around the doors are difficult to seal 5 against the entrance of heat into the interior of the refrigerator.

An object of the present invention is to make a simple and effective door sealing construction for refrigerators.

10 In order to attain this object, there is provided, in accordance with one feature of the invention, a groove extending entirely around the door adjacent the edge thereof in which a sealing strip is inserted and anchored.

15 These and other features of the invention will be more fully brought out in the following description and the accompanying drawings, wherein:

Figure 1, is a view in perspective of a portion of a door made in accordance with the present invention.

Figure 2, is a sectional, perspective view through a door made in accordance with the present invention, the door being shown in a 25 closed position in a door opening of a refrigerator.

Figure 3, is a view, also in sectional perspective, showing the method of fastening the sealing strip in position.

30 Figure 4, is a view in side elevation of a staple used to hold the sealing strip in place.

Figure 5, is an enlarged and cross sectional view of a sealing strip; and

Figure 6, is a sectional view illustrating 35 modified means for fastening the sealing strip in position.

Referring to the drawings in detail, a refrigerator door A is composed of frame members 2 and 3 with an interior enamel coated 40 metal plate 4 held in position by securing strips 5 which engage the outer edges of the plate 4 to hold it firmly in position. Sheets 7 and 8 of insulating material are affixed in position interiorly of the door by means of strips 9 and 10 in a customary manner.

A door cover plate 11 is enameled metal bent downwardly around its outer edge as at 45 12 to form a continuation of the outer edge, as at 12, to form a continuation of the outer door covering about the edges of the door,

the edge thereof being bent inwardly as at 13 to closely engage the door frame members 3. A groove 14 is cut in the wooden frame member 3 about the entire door, closely adjacent the outer edge thereof, being 55 preferably cut to slope outwardly toward the outer edge of the door, as shown, to hold a sealing strip B outwardly adjacent the extreme outer edge of the door and against the inturned edge 13 of the door cover plate 60 11.

The sealing strip B comprises a central core 16 of cushioning material with an outer covering 17 of fabric, or other suitable material. The covering 17 is wrapped about 65 the core to closely encircle it, and is sewed, or otherwise secured, as at 19, to provide an extension 18 projecting outwardly from the body portion of the sealing strip. This projecting portion 18 is inserted in the grooves 70 14 in a continuous strip about the entire outer edge of the door and is securely fastened in position within the groove by driving staples 20, or other securing means, through the frame member to penetrate the portion of the 75 sealing strip inserted in the grooves 14. The outward sloping of the grooves 14, as shown, positions the rounded body portion of the sealing strip outwardly toward the outer edge of the door, so that upon closing the 80 door the sealing strip will engage the body of the refrigerator and be partially flattened to have continuous sealing engagement with the body of the refrigerator and the inturned edge 13 of the door covering plate 11 completely around the door opening.

The body of the refrigerator, which is of a well known type of construction, is indicated in Figure 2. A frame member 21 has frame members 22 and 23 secured thereto. The outer walls of the refrigerator are covered 85 with enameled plates 24 and 25. A strip 26 of wood is secured to the inner side of the frame member 21 to conform to the offsetting 90 of the door construction. The door does not seat closely in the door opening as is clearly shown in Figure 2, being separated therefrom sufficiently to prevent condensation of moisture in this portion of the refrigerator, as would occur if the door were arranged to 100

seat tightly in the door opening. The inner enameled lining of the refrigerator is indicated at 27 and is of any suitable construction.

5 In the form shown in Figure 6, the sheathing strip B is held in position between the edge of the plate 12 and the edge of the door.

I claim:

10 In a refrigerator door having a body portion provided with plane edge faces, a resilient packing strip having a rounded body portion provided with a flange adapted to engage the plane edge faces of the door, and
15 an enameled metal sheathing for the door having inturned edges formed to engage the flange carried by the packing strip whereby the latter is retained between the plane edge faces of the door and the inturned edges of the metal sheathing.

20 In testimony whereof I affix my signature.
GEBHARD C. BOHN.
